ABSTRACT OF THE DISCLOSURE

A disposable tent formed of tubular stock has one gusset-tucked in end which is sealed, and the other end is open and provided with a draw string for closing the same. The tent is staked to the ground across less than the diameter of the tube at the open end, and, also, at the sealed end providing a ground cloth portion and a tent portion. A single line fastened to the top of the tube adjacent the open end holds the staked tent in erected position. In one form, the tent is made of light weight plastic film in tubular form.

An important object of the invention is to provide a simply constructed, light weight tent which may be erected for use by a single line.

A further object of the invention is to provide a disposable, light weight tent made of plastic film in tubular form.

A still further object of the invention is to provide a tent of simple construction formed of tubular stock having one sealed end and one open end and a very simple means for erecting the tent.

These and other objects and advantages of the invention may be readily ascertained by referring to the following description and appended illustrations in which:

FIG. 1 is a perspective view of tubular stock used for the construction of the tent according to the invention;

FIG. 2 is a perspective view of one form of tent made according to the invention, illustrating the erected position of the tent;

FIG. 3 is a partial perspective view of the open end of a tent illustrating one means of closure for the tent;

FIG. 4 is a partial perspective view of the open end of a tent according to the invention showing a modified means of closure for the tent; and

FIG. 5 is a perspective view of a modified form of the tent in erected position ready for use by an occupant.

In general, the invention provides a tent which is composed essentially of tubular sheet stock, having one end sealed shut and the other end open but closable when desired. The tent is staked to the ground along the sealed end and adjacent the open end at less than the diameter thereby forming a floor or ground cloth for the tent. The tent is arranged to be erected by a single line attached to a point near the open end and extended upwardly. The tubular stock may be made of plastic film or sheeting in tubular form, and such plastics as polyvinyl chloride and its copolymers, vinylidene chloride-vinyl chloride copolymers, regenerated cellulose, cellulose derivators, polyvinyl alcohol, polystyrene, nylon, polyethylene, rubber hydrochloride (Pliofilm) etc. may be used for tents of very light weight and which may be inexpensive enough for disposal after one or several uses. Tubular stock of fabric which may be plain or impregnated with plastics, rubber, or similar waterproofing material may, likewise, be used for the tent material. Also, the fabric may be vegetable fibers, mineral fibers or plastic fibers. The essence being that the material is tubular stock, and the term, tubular stock includes all such material. The tents may be made in a variety of sizes, and the two major dimensions to be determined are the diameter of the tube

2

stock and length thereof. Small, one-man tents may be made of tubular stock of 6 to 8 feet diameter, and larger tents may be made of tubular stock of 10, 12, 14 or more feet. The length may be from 8 to 12 feet or more depending upon the desires of the users. The larger tents may be any length above about 10 feet or more.

In the illustrations, a tubular stock as shown in FIG. 1 comprises a tube 10 having an open end 12 at one end and an open end 14 at the opposite end. As pointed out above the stock may be plastic, fabric, or combinations thereof of the desired size. A tent is made of the tubular stock by tucking in the sides of the end, for example, forming gussets 16 and 18 of end 14 and sealing the end closed by means of a seal 20. Where fabric is used the end is sewn together, and where plastic is used the end may be heat sealed closed or otherwise sealed shut as by an adhesive or the like. In the form illustrated in FIG. 2, a pair of metal grommets 22 and 24 are secured in the sealed end 20 for staking the tent to the ground. Adjacent the opposite end a second pair of grommets 26 and 28 are secured in the side of the material which is folded over, and the distance between the grommets 26 and 28 is considerably less than diameter of the material. Thus, when the tent is staked to the ground by means of stakes or the like in the grommets there is provided a floor 30, which is less width than the diameter of the tube. In the form illustrated, the tent may be provided with metal grommets which are fastened in the material. Particularly with plastic material, however, reinforcing members may be sealed to the material at the point where a hole is to be provided, thus forming a plastic grommet for staking the tent to the ground. For holding the tent in erect position a tab 32 is sealed to the tube at approximately the same position from the end of the tent as grommets 26 and 28 but is midway on the material 30 between the two grommets. The tab 32 is provided with a grommet 34 for the attachment of a line. The tab may be sewn on fabric, and sealed on plastic by such conventional means as heat sealing, adhesives or the like. The placement of the grommets 26 and 28 and the tab 32 leaves a loose end 36 of the tent which may be pulled together closing the same. One form of closing is by means of a draw string 38, FIG. 4, which is placed inside a tube or hem 40 formed at the edge of the material by folding the same back and sealing it along a seal line 42. The grommets 26 and 28 and the tab 32 should be placed a sufficient distance from the edge 12 of the tent so that it may be drawn together for tightly closing the tent opening. A different form of closure for tent opening is shown in FIG. 3, where a tent 50 having a floor 52 is provided with a series of grommets 54 adjacent the edge 56 of the opening of the tent 50. A line 58 laced through the grommets provides means for forming a draw string for closing the end of the tent. Obviously, other types of closures may be used such as snaps, buttons or the like.

As illustrated in FIG. 5, a tent 60 is easily erected by means of a single line 69, which is secured to the open end of the tent. This line may be secured to an elevated structure or by means of an angle 72 to another line 62 which is attached to a tree 65 at one end and to a stake 67 at the other end. The tent 60 is made of a light weight plastic film and the end 64 is gusseted and sealed. The tent is staked to the ground by the stakes 67 which are merely driven into the material into the ground at four positions, as above-mentioned, to hold the tent down and form a floor 68 in the tent 60. To erect the tent a line 69 is passed through a pair of holes 70 and 71, at approximately the same position as the tab 32 of the tent of FIG. 2, spaced back from the end 63 of the tent 60. The line 69 is secured to the rope clamp 70 which is mounted on the line 62. The clamp 70 is very simply an apertured angle with the line 62 passing through one opening and

the line 69 secured to the other opening. The angle may then be moved up and down the line 62 to put the desired taughtness on the line 69. For simple erection, a longer line than 69 could be connected to the holes 70 and 71 and fastened to a pole or tree or other high support thereby holding the tent in erected position. The double line, however, provides flexibility in the event of wind, and prevents over straining the light weight plastic material of the tent.

A tent made of 9 foot tubular stock about 8 feet in length, and made of 1½ mill Marlex, made by Phillips Petroleum, which is a rubber impregnated polyethylene, or equivalent resin, weighs not more than about 6 ounces and may be readily folded into a package of about 4 inches by 5 inches and less than a half inch thick. Thus, the tent may be disposable since the material is very inexpensive. The Marlex is waterproof and provides good wind protection, thus it is ideal for hikers, hunters, fishermen and the like who may be caught from their base of operation and are required to spend the night in the elements. Even though such a light weight material is intended to be disposable it may be used several times to provide shelter from wind and moisture, but its cheapness permits it to be discarded after one or a few uses. By providing plastic material which is essentially a vapor barrier the tent provides a waterproof ground cloth, which is essential to keep the user warm and dry in adverse weather conditions. Where the tent is made of fabric, the bottom may be given an extra coat of plastic or the like to make it waterproof, and such a tent may be reusable many times.

While the invention has been described in reference to particular embodiments, there is no intent to limit the spirit or the scope of the invention to precise details so set forth.

I claim:

1. A tent comprising a main body of unbroken tubular material having one closed end and one open end, said closed end having the opposed sides tucked in as gussets and sealed in closed position, said open end including releasable means for closing the same for use, said releasable means being adapted to close said open end by reducing the effective area of said open end, means for staking said closed end to the ground, means for staking said tubular material to the ground at a distance from

said closed end and spaced from said open end, and said means for staking said tubular material being spaced across said tubular material a predetermined distance apart and in alignment with said closed end to form a generally rectangular floor for said tent and provide a substantial portion of tubular material extending above said floor forming the covering tent portion, and means inclusive of a line secured to said tubular material at a point circumferentially aligned with said means for staking said tubular material and spaced from said open end for supporting said substantial portion of tubular material in an erected position in the absence of support means within the interior of said tubular material.

2. A tent according to claim 1 in which said tubular material is a plastic film.

3. A tent according to claim 1 wherein said tubular material is a fabric.

4. A tent according to claim 1 wherein said releasable means for closing open end is a line in a hem at the open end of said tent.

5. A tent according to claim 1 wherein said means for staking said closed end includes a pair of spaced apart grommets.

6. A tent according to claim 5 wherein said grommets are metal secured in the seal closing said closed end.

7. A tent according to claim 5 wherein said grommets are a pair of spaced apart plastic reinforced holes in said closed end.

8. A tent according to claim 1 wherein said means for supporting said substantial portion is a pair of spaced apart holes and said line is threaded through said holes at one end and secured in an elevated position at the other holding said tent erected.
